UNITED STATES PATENT OFFICE

2,265,491

CAN OPENER

Wallace O. Powers, Springfield, Mass.

Application May 27, 1940, Serial No. 337,379

2 Claims.

(Cl. 30—15)

My invention is in the nature of an improvement in a can opener which may be used for various purposes, and the principal object thereof is directed to the provision of a unique and novel arrangement of parts which is characterized by its comparative simplicity when compared with what has come before it.

Heretofore, the necessity for removing the dis-united top of a can which has been separated from its can by an opener of the common and well-known type has been hindered by the fact that such tops oftentimes drop into the can upon their subsequent severing therefrom, with the result that the operator is oftentimes cut or otherwise injured in his attempts to remove the same. With such an objectionable feature in mind, my invention has thus been devised to overcome the same.

It is a further object of my invention to provide a unique and novel combination and arrangement of parts which is sure and positive in its operation and which is characterized by its relatively low cost of manufacture and by its combination of elements which are arranged in a distinctive and unique manner, so as not only to be accessible readily for any use thereof, but also to encourage the use of the same so as to make their sales increase. That is to say, the device is constructed so as to be of what might be called the "jiffy" type and it is especially susceptible to easy assembly and disassembly upon cans and the like with which it is used so as to create a demand for the same in stores and the like.

The device of the invention is so constructed that it may be readily and quickly attached to the object or objects which it is desired to operate upon, and it has the added advantage of being simple in its construction as well as sanitary so that dust, rust and other objectionable materials do not fall into the food or liquid contents.

Other prime objects of my invention include first, the provision of a sturdy and simplified construction of a can opening device of the character above referred to; second, the securement of a higher degree of accuracy in the performance of work which may be performed therewith than has heretofore been possible; third, the attainment of a higher degree of speed of construction of the device due to its simplification in construction and its unique composition of parts; fourth, the attainment of a flexibility or a capability of easy adjustment by which a large variety of work can be produced by means of the same device; fifth, the achievement of greater ease in adjustment and in repairs; sixth, the provision

of an improved can opening device which may be made more economically and with fewer operations in the manufacture of its parts, as well as in the assembly of the same, than prior devices known in the art, and seventh, the provision of a device in which the parts, when once assembled, are positively and securely retained in operative relation and cannot be separated from each other either accidentally or otherwise.

With the foregoing and various other novel features and advantages and other objects of the inventive idea involved as will become more apparent as the description proceeds, my invention consists in certain novel features of construction and of a combination and arrangement of parts and is capable of receiving a variety of mechanical expressions as will be hereinafter more particularly pointed out in the claims hereunto annexed and will be more fully described and referred to in connection with the accompanying drawing which shows a satisfactory constructional example of the invention without defining its limits, and wherein:

Fig. 1 is a side elevational view of the device of my invention shown in cooperation with a can; and

Fig. 2 is a top plan view of the device of my invention.

Referring now to the drawing more in detail, wherein similar reference figures refer to like parts, and referring more particularly to the preferred form of my invention which has been selected for illustrative purposes, I have shown an essential feature of the device of my invention which is a can opener. This may take various forms, but according to the preferred embodiment of my invention, it consists of a handle member working in conjunction with an operating member. Such a can opener as I refer to includes a handle member 12 which has a toothed gear 14 rotatably secured at one end thereof. An operating member 16 has a sharp cutting jaw member 18 at one end thereof and the members 12 and 16 are pivoted to each other substantially as shown at 19 whereby the two members may be brought into closer adjacency with each other by manually gripping and squeezing the two members together with the result that the cutting jaw member 18 pierces a top of a can C when the operating member is squeezed upwardly as can be appreciated by an examination of Fig. 1 where it will be seen that the jaw has pierced the top of the can.

A rotating operating member 20 is fixedly secured to the toothed gear 14 so that as the oper-

ating member 20 is rotated the toothed gear 14 is likewise rotated.

To operate the opener, it may be held in the left hand and the tooth gear 14 is "hooked" under the rim R of the can C. By manually squeezing the operating member 16 upwardly towards the handle member 12 the cutting jaw member 18 which overlies the top of the can substantially as is shown in Fig. 2 pierces the top at the edge thereof near to the rim R. As the rotating member 20 is rotated, the toothed gear 14 is likewise rotated and as it moves forwardly around the rim of the can, the other parts of the tool are likewise moved and the jaw member continues to cut the top of the can as indicated by the cut X in Fig. 2. By continuing to rotate the rotating member the can may be completely encircled and the top of the can may be completely removed from the can.

Associated with the handle member 12 is a spring member 30 which is pivotally secured thereto at 32 and which projects at an angle therefrom towards a free end portion 34 to which an attaching means is secured. This means may take the form of a magnet or a suction cup. In the drawing, a spring member is shown to which a suction cup 36 is pivotally secured and is rotatable relative thereto by means of a bolt or rivet 38 and nut 39, although it will be understood that the suction cup is shown merely for purposes of illustration and that a magnet could be substituted therefor with little difficulty.

The spring member may take various forms but in the form shown it is made of a flat spring-like metallic material although it is to be understood that any other type of spring may be used so as to facilitate the easy manipulation of the spring member and its associated attaching means. This spring member may be detachably secured to the handle member so that it is adapted for slipping over said handle member, although in the drawing it will be understood that it is secured thereto at 32 by a pivotal arrangement.

If it is desired, the spring member may be adjustable so that its length may be varied to make it adaptable for varying conditions. That is to say, because cans vary in their sizes, it may become desirable, if not necessary, to provide an adjustable means whereby the spring member may be changed in its length so as to overlie the tops of different cans of different sizes.

The attaching means 36 is adapted to overlie the top of the can C so that when it is desired to remove the top of the can the attaching means may be called into play by merely moving the spring member 34 in the desired direction so as to enable the attaching means 36 to become engageable with the top of the can. The spring being easily adjustable, the attaching means can be easily brought into the desired position.

As the cutting operation commences, the can is rotated relative to the device whereby the pivotal arrangement between the attaching means and its component spring member is called into use. As the can is rotated, the attaching means, of course, remains stationary relative to the remainder of the device of my invention by virtue of the pivotal arrangement which permits the spring member 34 to turn upon the bolt 38.

If a suction cup is used for the attaching means, all that is required in order to loosen the same from the can is to squeeze its sides together so as to break the vacuum created thereunder. The vacuum having been broken, the attaching means is easily removed. If a magnet is used as the attaching means, all that is required in order to loosen the same from the can is to upset the magnetic attraction between the magnet and the can whereby the two units are quickly and easily disassociated.

My invention has the additional feature of being adapted for hanging purposes wherever it is desired to place the same when not in use which is a feature very much to be desired.

Manifestly the specific details of construction may be considerably varied from those herein shown and described without involving any departure from the principle of the invention or 20 sacrificing any of the advantages inherent therein. While I have described my invention in this specification in great detail and particularly with respect to the present preferred form thereof, it is not desired to be limited thereto since many changes and modifications may be made therein without departing from the spirit and scope of the invention.

The invention may be embodied in other specific forms without departing from the essential 30 characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

40 What it is desired to claim and secure by Letters Patent of the United States is:

1. The combination with the pivotally connected members of a can opener and associated means for cutting a cover from a can of means 45 for retrieving said cover comprising, a spring member having an end pivotally connected to one of said members providing a resilient free end for extending over the cover of a can, and a suction cup secured to the free end of said member adapted for suctionally attaching to said can cover, said spring member and suction cup adapted and arranged to yieldingly urge the cover upwardly when cut from the can and swingable to move the cover away from the opening in said can.

2. The combination with the pivotally connected members of a can opener and associated means for cutting a cover from a can of means for retrieving said cover comprising, a flexible 60 spring member having an end connected to one of said members providing a resilient free end for extending over the cover of a can, and a suction cup secured to the free end of said member adapted for suctionally attaching to said can cover, 65 said spring member and suction cup adapted and arranged to yieldingly urge the cover upwardly when cut from the can and swingable to move the cover away from the opening in said can.

WALLACE O. POWERS.
